GUITAR BAR OR STEEL HAVING A
ROTATING CONTACT FACE

Fremont W. Peasley, Sunnyvale, Calif.

Application July 17, 1947, Serial No. 761,669

2 Claims. (Cl. 84—319)

1

This invention relates to a bar or steel for Hawaiian and electric guitars, and the primary object of the invention is to provide a bar or steel having a rotating contact face which will freely rotate over the strings and eliminate the rasping sound and uneven tone that is present when ordinary bars or steels are used in the conventional manner.

Another object of the invention is to provide a cylindrical bar or steel having a rotating contact face that can be used for contact with the strings of a stringed instrument or the bar can be slightly rotated in the user's hand to present a fixed contact face with the strings.

There are many advantages that are inherent to a bar or steel of this type; among them are that the bar or steel can be used by professionals in accomplishing intricate positions on the strings to produce certain notes and vibrations that cannot be achieved with a conventional bar or steel. A bar or steel constructed in accordance with the invention provides a rotating as well as a fixed contact face for the strings, a feature that is not present in conventional bars and steels.

Another object of the invention is to provide a spring suspension for the rotating contact face that will tension the contact face so that a true center is always available, thereby maintaining the contact face in the same position at all times, applying the same amount of pressure at all times, which action is not available in devices not using the spring suspension construction.

With the above and other objects and advantages in view, the invention consists of the novel details of construction, arrangement and combination of parts more fully hereinafter described, claimed and illustrated in the accompanying drawings in which:

Figure 1 is an elevational view of an embodiment of the invention shown in the position in which it will be held in the musician's hand during the playing of an instrument;

Figure 2 is a rear end elevational view of Figure 1;

Figure 3 is a transverse sectional view on the line 3—3 of Figure 1 and

Figure 4 is a longitudinal sectional view on the line 4—4 of Figure 2.

Referring more in detail to the drawings, the bar or steel which is constructed in accordance with the invention and which is adapted for use with the strings of a Hawaiian or electric guitar is designated by the numeral 10.

The bar or steel 10 comprises a cylindrical body portion 11 having a bullet shaped nose 12 and a flat end 13.

Extending longitudinally of the body for approximately the entire length thereof, is a concave recess 14 which is open through the wall of the body portion 11.

2

The forward end of the recess 14 is provided with a conical shaped seat 15 while the opposite end is flat as at 16 and provided with a semi-spherical seat 17 centrally thereof.

5 Mounted for rotation within the recess 14 is the contact face or bar 18 which is also cylindrical in shape, and is of a length to be received within the seat 15 due to the slightly rounded forward end 19 thereof.

10 The bar 18 is provided with centrally located inwardly extending cylindrical sockets 20 and 20' respectively, in which are positioned the coil suspension springs 21 and 21' respectively.

The spring 21 engages and applies pressure to a roller bearing or ball 22 which is positioned in the seat 15, and the spring 21 engages and applies pressure to a roller bearing or ball 22' which is positioned in the seat 17. Thus the bar 18 is mounted for free rotation on the suspension springs 20 and 20'. This manner of suspending or mounting the bar provides even pressure or tension on the bar to maintain the bar in the same position at all times to provide even contact with the strings of an instrument. The surface 25 of the bar is extremely smooth in finish, so that no obstructions are provided for contact with the strings to mar the tone of the instrument.

As seen from Figure 2, the end 13 for a portion thereof is cut away at 23 so that the end, at this portion, is substantially the same size as the end of the bar 18. At a point in alignment with the cut away portion of the end is an aperture 24 which is adapted to receive a sharp pointed instrument. With the instrument, not 30 shown, inserted in the aperture 24, and pressure applied thereto, the springs 21 and 21' can be compressed so that the bar can be removed for replacement or the like, or new springs or balls may also be replaced in the assembly.

In use, the bar or steel 10 lies between the second and third fingers of the musician's hand. In this position, the third finger can rest on the strings of the instrument to mute any noise which comes from lifting the bar or steel between notes.

45 Should the musician desire a fixed contact face in lieu of the rotating contact face produced by the rotating bar 18, the bar or steel 10 can be slightly rotated in the musician's hand to present the body portion 11 to the strings. Such action 50 can even be accomplished during the playing of the instrument.

The shape of the nose 12 is a popular shape with professional musicians, since it presents a surface which will not cause the bar or steel to catch on the strings during the playing of the instrument.

There has thus been provided a bar or steel which will reduce the friction between the bar and strings, will be quicker to manipulate, will produce less noise on the strings, eliminate any 55 scraping sound between the bar and strings. The 60

spring suspension of the bar permits vibrations of the strings that cannot be produced with a bar having a fixed contact face, and the bar enables beginners or students to produce professional sounding notes.

It is believed that the advantages and manner of use of the bar or steel will be apparent to those skilled in the art, and it is to be understood that changes in the minor details of construction, arrangement and combination of parts may be resorted to, provided they fall within the spirit of the invention and the scope of the appended claims.

Having thus described the invention, what is claimed as new and desired to be secured by Letters Patent is:

1. A device of the character described, comprising a cylindrical body portion, a concave shaped recess in said body portion extending through the wall thereof, ball engaging seats at the opposite ends of said recess, a smooth string contact face or bar positioned in said recess, cylindrical-shaped recesses at opposite ends of said bar, balls in said ball engaging seats and spring

suspension means in the recesses in said bar and adapted to engage said balls for rotatably mounting said bar in said recess.

2. The invention as in claim 1, wherein said body portion has a bullet shaped nose, and a flat rear end, and an aperture is provided in the center of said rear end to receive means for compressing said spring suspension means, whereby said bar may be removed from said body portion 10 for the replacement thereof.
